BEATER APPARATUS

José Louis Schaan, Paris, and Marc Lamort de Gail, Vitry-le-Francois, France, and Arnold J. Barea, Pittsfield, Mass., said De Gail assignor to Etablissements E. & M. Lamort Fils, Vitry-le-Francois, France, a society of France

Application July 9, 1953, Serial No. 367,008

2 Claims. (Cl. 92—27)

In the manufacture of paper, cardboard or the like it is usual to disintegrate the primary materials, whether fresh materials or textile wastes in apparatus such as hollanders or mills with disc-like, conical or other beaters.

Such machines comprise a fixed member and a movable member between which the material to be treated passes. These members are provided with blades or segments of hard material such as stainless steel, bronze, lava and various agglomerates. The conception which has hitherto governed the construction of such machines has been to disintegrate the material to be treated by means of the hardest possible members, which results in various inconveniences and particularly a disadvantageous shortening of the fibres which the material contains and a reduction of their felting capability.

According to the present invention these disadvantages are minimized or reduced by causing the material to be treated to pass between members of which at least one is provided with agitating means of an elastomeric material the elastic deformation of which is of the order of that of rubber, or rests on the frame of the machine which supports it through the intermediary of a mass of material having the same characteristic.

Preferably, the agitating means are formed of bars extending in a direction perpendicular to the direction of relative displacement of the disintegrating members.

More particularly, and especially in machines whereof the disintegrating members are in the form of cones, or frustums of cones, that member which is provided with the novel bars as aforesaid (for example, in a conical beater the outer cone) constitutes or is mounted on one of the walls of a chamber within which pressure can be varied in such a manner as to effect a deformation of said wall.

Such deformable wall may be mounted by the intermediary of at least one elastically deformable member subject to the pressure variation within the chamber.

Such a wall may for example be made of rubber.

An embodiment of the invention will be described solely by way of example with reference to the accompanying drawings wherein:

Figure 1 is a longitudinal section of a frusto-conical mill, and

Figure 2 is a section on an enlarged scale on the line II—II of Figure 1.

The material to be treated is suspended in a liquid and supplied under pressure to an entrance chamber 1 of the machine. A screw feeder 2 is mounted on a shaft 3 together with a beater plug 4 of frusto-conical form, the details of mounting and sealing of the shaft 3 in the machine being clearly evident from the drawing. Under continuous rotation of the shaft 3 the screw feeder 2 forces the material to be treated into a beating chamber formed between the inner member or cone 4 and a co-operating hollow outer member in the form of a female cone 5 constituting the disintegration means, and the treated fibrous pulp suspension is discharged from the machine by way of a duct 6.

2

According to one feature of the present invention, the male cone 4 has attached thereto elastomeric agitating members in the form of rubber bars 7 having bases of trapezoidal section, these bars being maintained in position by bars 8 of metal or other means the cross-sections of which are complementary to the cross-sections of the bases 7a of the bars 7. The bars 8 are secured to the cone 4 as shown in Figure 2 by screws 9.

The female cone may be provided with similar elastomeric agitating members or bars.

According to another feature of the invention, the female cone is formed of a conical member 10 of rubber or metal, the margins of which are secured to rubber members 11 fixed to a hollow support or casing 12 of conical external form. The casing 12 and the cone constituted by members 10 and 11 together comprise an airtight chamber 13 the volume of which may be varied or within which the pressure can be varied by connecting it to a source of fluid under pressure shown schematically at 13a (for example air) by way of a connection 14.

Experiments which have been made show that with apparatus as described there is obtained a beating of the pulp comparable to a large extent with the action of the rods or hammers in the old type of paper mill, and a long fibre imparting to papers high mechanical resistance without the need for recourse to long fibre celluloses. Microscopic examination of the pulps in course of treatment moreover permits the operation of progressive fibrillation to be followed and controlled without interruption.

More particularly, in the case of pulps of waste paper disintegrated to a greater or less extent in the modern preparatory machines operating with the aid of liquids, there is achieved with the apparatus as above described maximum preservation of the fibres which have already been disintegrated. The nodules which always subsist are rapidly reduced into elementary fibres and the pulp simultaneously thus receives a desirable thickening, always without shortening of the fibres.

The flexible agitating means above described may be applied to all known disintegrating apparatus, such as hollanders and disc or cone beaters, without modification of mechanical means for relative adjustment of the mobile and fixed members. However, replacement of the usual rigid mechanism by a pneumatic means affording regulable elastic pressure permits the obtaining of apparatus of maximum efficacy. According to the kind of material to be treated, such elastic pressure may be exerted on either the fixed bars or the movable bars, the relative positions being determined by positive or negative deformation, that is by expansion or contraction within the chamber.

We claim:

1. A beater apparatus comprising, in combination, a hollow support; a hollow outer member having an inner surface forming a beating chamber; resilient mounting means for mounting said outer member within said support so that an airtight chamber is formed between the inner surface of said support and the outer surface of said outer member, said airtight chamber being adapted to communicate with a source of fluid under pressure so that the volume of said airtight chamber and consequently the volume of said beating chamber may be varied by varying the fluid pressure prevailing within said airtight chamber; a plurality of first elastomeric agitating members secured to the inner face of said outer member and projecting inwardly into said beating chamber; an inner member arranged within said beating chamber; a plurality of second elastomeric agitating members secured to said inner member and projecting outwardly into said beating chamber, said second agitating members being spaced from said first agitating members; and moving means for moving said inner member relative to said

outer member so that when said inner member is moved relative to said outer member a substance within said beating chamber is beaten by said agitating members.

2. A beater apparatus comprising, in combination, a hollow support; a hollow outer member having an inner surface forming a beating chamber; resilient mounting means for mounting said outer member within said support so that an airtight chamber is formed between the inner surface of said support and the outer surface of said outer member, said airtight chamber being adapted to communicate with a source of fluid under pressure so that the volume of said airtight chamber and consequently the volume of said beating chamber may be varied by varying the fluid pressure prevailing within said airtight chamber; a plurality of first elastomeric agitating members secured to the inner face of said outer member and projecting inwardly into said beating chamber; an inner member arranged within said beating chamber; a plurality of second elastomeric agitating members secured to said inner member and projecting outwardly into said beating chamber, said second agitating members being spaced from said first agitating members; feed means op-

eratively associated with said inner member for feeding a substance to be beaten into said beating chamber; and moving means for moving said inner member relative to said outer member and for moving said feed means so that when said inner member is moved relative to said outer member a substance fed into said beating chamber by said feed means is beaten by said agitating members.
